PACKAGE AND PARCEL SHELF

Frederick W. Kent and William F. Sievert, Milwaukee, Wis., assignors to Badger Engraving Company, Inc., Milwaukee, Wis., a corporation of Wisconsin

Application March 5, 1948, Serial No. 144,916

Term of patent 14 years

(Cl. D33—3)

To all whom it may concern:

Be it known that we, Frederick W. Kent and William F. Sievert, citizens of the United States and residents of Milwaukee, in the county of Milwaukee and State of Wisconsin, have invented a new, original, and ornamental Design for a Package and Parcel Shelf, of which the following is a specification, reference being had to the accompanying drawing, forming part thereof.

Figure 1 is a perspective view of a package and parcel shelf embodying our new design, said view showing the shelf in its closed, inoperative position; and

Figure 2 is a perspective view of the shelf shown in its open, operative position.

The dominant features of the present design

reside in those portions shown in full lines on the drawing.

We claim:

The ornamental design for a package and parcel shelf, as shown and described.

FREDERICK W. KENT.
WILLIAM F. SIEVERT.
